J. M. NAUL,
ELECTRIC SWITCH,
APPLICATION FILED AUG. 14, 1917.

1,383,330.

Patented July 5, 1921.

By his Attorney James M. Naul
Fannie Davis Marvine Edwards
Att'y.

UNITED STATES PATENT OFFICE.

JAMES MYRVEN NAUL, OF PITTSFIELD, MASSACHUSETTS, ASSIGNOR, BY MESNE ASSIGNMENTS, TO AMERICAN BOSCH MAGNETO CORPORATION, OF NEW YORK, N. Y., A CORPORATION OF NEW YORK.

ELECTRIC SWITCH.

1,383,330.

Specification of Letters Patent. Patented July 5, 1921.

Application filed August 14, 1917. Serial No. 186,159.

To all whom it may concern:

Be it known that I, JAMES M. NAUL, a citizen of the United States, residing at Pittsfield, in the county of Berkshire, State 5 of Massachusetts, have invented certain new and useful Improvements in Electric Switches; and I do hereby declare the following to be a full, clear, and exact description of the invention, such as will enable others 10 skilled in the art to which it appertains to make and use the same.

The present invention relates to electric switches in which locking mechanism controlling the operation thereof includes a 15 removable member, such as a key, so that, as a practical matter, unauthorized change of the circuits is prevented. In the preferred form in which the mechanism may, if desired, be embodied in a single structure, 20 the switch is adapted to control a plurality of electric circuits and has a switch arm movable to a plurality of positions in contact with the switch studs to which those circuits are respectively connected, the locking mechanism being adapted to lock the switch at any of said positions. Whether or 25 not the mechanism is embodied in a single switch structure, the locking mechanism comprises, in its preferred form, a lock 30 plate movable with the switch arm, and a cam which may be moved by the removable member to one position in which the lock plate is freely movable to permit movement of the switch arm or to another position in 35 which the lock plate is held against movement to prevent change of the circuits. In this construction a handle is provided for moving the switch arm and the lock plate when released by the locking mechanism. 40 Furthermore, the construction is such that in the position in which the removable member may be removed from the switch, the switch arm is locked by the locking mechanism, and in the position in which the 45 switch arm is freely movable, the removable member is retained in the switch.

The electric circuits may include the lighting circuits of an automobile or the like, as for example, the circuits of the head lights, side lights, tail light, etc., the switch arm being connected to the source of current supply therefor. The electric circuits may also include the ignition circuit

of the engine. By arranging the switch so that, besides the several positions for the 55 lighting circuits, there is a position in which the ignition system is rendered inoperative, the driver may lock the switch against unauthorized starting of the engine as well as against unauthorized change of the lights. 60 In the construction specifically described hereinafter for this purpose, the switch has a stud connected to the ignition circuit, and a grounded member movable with the switch arm is arranged to contact therewith 65 only in the zero position of the switch, to thereby render the ignition system inoperative at that time.

In the accompanying drawing showing as an example, the preferred form of a single 70 switch structure for controlling the lighting and ignition circuits on an automobile or the like,

Figure 1 is a front view of the switch in zero position, the key being removed; 75

Fig. 2 is a section on line 2—2 of Fig. 1, the handle being shown in full side view in broken lines and the key being inserted;

Fig. 3 is a rear view of the front part of 80 the switch;

Fig. 4 is a front view of the rear part of the switch;

Figs. 5, 6, 7 and 8 are diagrammatic views showing the switch in the positions marked 0, 1, 2 and 3, respectively; and 85

Fig. 9 is a wiring diagram.

The switch has a cup-shaped casing 1 of metal with a flange 2 adapted to be screwed to a support. The base block 3 of insulating material is fastened to the casing by 90 screws and forms therewith an inclosed chamber for the reception of the operating parts of the switch. The handle 4 carries a spindle 5 journaled centrally in the casing and riveted to the lock plate 6, these parts 95 being arranged to turn between the limits determined by the terminal faces of the boss 7. Five slotted studs of copper, 8, 9, 10, 11 and 12, are held rigidly in the base block 100 and are engaged by binding post screws, such as shown at 13, to which the circuits to be controlled by the switch are attached at the back. The central hollow stud 14 of copper has a connecting screw 15, and provides at its inner end a journal on which 105 the switch arm can turn. The end of the

journal is forced back against the copper washer 16 after the switch arm is in place on the journal, and forms a good electrical connection between the parts. The switch 5 arm is made up of two copper segments 17 spaced apart by the metal washer 18 and having opposite flanges of different angular extent. The ring 19 of insulating material is riveted to the switch arm and is provided with two holes 20 into which project the two pins 21 from the lock-plate 6. The slot in the stud 10 is higher than those in the other studs and the two segments 17 are spaced apart axially to such an extent that 10 the stud 10 is not engaged thereby, whereas the other studs 8, 9, 11 and 12 are engaged thereby when the switch arm is moved upon turning the handle 4. A bent copper strip 22 is fastened to the lock plate 6 and is arranged 15 to engage the top of the stud 10 which is longer than the other studs, but to pass over the other studs without engaging them. This strip is grounded on the lock plate, and thereby grounds the stud 10 when 20 in contact therewith.

The locking mechanism comprises a cam 23 held in place by the flat spring 24, and a key 25 which can be inserted in place and withdrawn therefrom only in that position 25 wherein the peripheral part 26 of the cam sets in a peripheral recess in the lock plate 6. In this position, the lock plate cannot be turned from its set position, irrespective of what that position may be, but when the 30 peripheral part 26 is turned about 180 degrees, in which position the key cannot be removed from the switch, the lock plate may be turned without interference by the cam. The flat spring 24 has a V-shaped portion 27 adapted to spring into the V-shaped groove 28 of the cam, when the cam is in either of 35 its two positions.

As will be seen from Fig. 9, the central stud 14 is electrically connected to one terminal of the battery 29, whereas the studs 9, 40 11 and 12 are connected to the dash and tail lights, the side lights and the headlights, respectively. The stud 8 is connected to the circuit breaker for the electric generator 45 which supplies current to the battery and lamps when the engine is running above a predetermined speed. The stud 10 is connected to the insulated element of the mechanical interrupter 30 of the magneto generator 30. In the 0 or "off" position of the switch, as shown in Figs. 1 to 5, the switch arm is disengaged from all the studs, and the grounded strip 22 is in contact with the stud 10, thereby disconnecting all of the 50 lights and rendering the ignition system inoperative by grounding the insulated terminal of the primary winding of the magneto. In position 1, as shown in Fig. 6, the switch arm contacts with the stud 8, thereby connecting the circuit breaker of the electric

generator to the battery. In position 2, as shown in Fig. 7, the switch arm contacts with the studs 8, 9 and 11, thereby connecting the source of current to the dash and tail lights, and also to the side lights. In position 3, as shown in Fig. 8, the switch arm contacts with studs 8, 9 and 12, thereby connecting the source of current to the dash and tail lights, and also to the headlights. In positions 1, 2 and 3, the strip 22 is disengaged from the stud 10, and also from the other studs. Thus the ignition system is rendered operative at the switch at all positions except the 0 position. The spring pressed ball 32 snaps into a recess of the lock plate 6 at each one of its four positions, to lightly hold the switch in that position. 70

It will be understood from the foregoing, that the switch may be locked in any of its positions 0, 1, 2 or 3, so that upon removing the key, unauthorized change of the circuits is, as a practical matter, prevented. Furthermore, when the switch is unlocked for operation, the driver may at any time interrupt the ignition for the engine by moving the switch to its 0 position. By locking the switch in this position, unauthorized starting of the engine is prevented. 75

Having thus described my invention, what I claim is:

1. In a single switch structure for controlling the lighting and ignition circuits on an automobile or the like, a plurality of switch studs connected to the lighting circuits, another switch stud connected to the ignition circuit, a switch arm having one position in which said stud is engaged thereby to render the ignition circuit inoperative and in which the switch arm is disengaged from the studs connected to the lighting circuits, and having other positions in which said stud is disengaged thereby to render the ignition circuit operative and in which the switch arm engages the studs connected to the lighting circuits, and locking mechanism, including a removable member, for locking said switch arm in any of said positions. 95

2. In a single switch structure for controlling the lighting and ignition circuits on an automobile or the like, a plurality of switch studs connected to the lighting circuits, another switch stud connected to the ignition circuit, a switch arm having one position in which the stud connected to the ignition circuit is grounded and the switch arm is disengaged from the studs connected to the lighting circuits, and having other positions in which the stud for the ignition circuit is disconnected from and the switch arm engages the studs connected to the lighting circuits, and locking mechanism, including a removable member, for locking said switch arm in any of said positions. 110

3. In a single switch structure for con- 120

controlling the lighting and ignition circuits on an automobile or the like, a plurality of switch studs connected to the lighting circuits, a switch arm having a position in which said studs are disengaged and having other positions in which said studs are engaged, a switch stud connected to the ignition circuit, a grounded member movable with the switch arm and engageable with the 5 stud connected to the ignition circuit when the switch arm is in the said position in which it is disengaged from the studs connected to the lighting circuits, and locking mechanism, including a removable member, 10 for locking said switch arm in any of said 15 positions.

4. In a single switch structure for controlling the lighting and ignition circuits on an automobile or the like; a plurality of 20 switch studs connected to the lighting circuits; another switch stud connected to the ignition circuit; a switch arm having one position in which the ignition stud is engaged and the lighting studs disengaged 25 thereby to render the ignition and lighting circuits inoperative, and having another position in which the ignition and lighting studs are disengaged to render the ignition circuit operative and the lighting circuits 30 inoperative, and also having a third position in which the ignition stud is disengaged and one of the lighting studs is engaged to render the ignition and lighting circuits operative; and locking mechanism, 35 including a removable member, for locking said switch arm in any of said positions.

5. In a single switch structure for controlling a plurality of electric circuits on an automobile or the like, a plurality of switch 40 studs connected to said circuits, a switch arm movable to several positions in contact with said studs, and locking mechanism for locking said switch arm in any of said positions, said locking mechanism including a removable member which can be removed from the switch only when said switch arm is locked in any of said positions by said locking mechanism.

6. In a switch for controlling a plurality 50 of electric circuits, a plurality of switch studs connected to said circuits, a switch arm movable to several positions in contact with said studs, a lock plate mechanically connected to said switch arm for movement therewith, and mechanism, including

a removable member, for engaging said lock plate to lock it against movement.

7. In a switch for controlling a plurality of electric circuits, a plurality of switch studs connected to said circuits, a switch arm 60 movable to several positions in contact with said studs, a lock plate mechanically connected to said switch arm for movement therewith, a cam having one position in which it engages said lock plate to lock it 65 against movement and having another position in which it is disengaged from said lock plate to permit free movement thereof, and a key for turning said cam from one to the other of its positions. 70

8. In a switch for controlling a plurality of electric circuits, a plurality of switch studs connected to said circuits, a switch arm movable to several positions in contact with said studs, and locking mechanism including a removable member, for locking said switch arm in any of said positions, the switch arm being locked by the locking mechanism when the removable member is in position to be removed from the switch, 75 and being unlocked by the locking mechanism when the removable member is in position to be retained by the switch. 80

9. In a switch for controlling a plurality of electric circuits, a plurality of switch 85 studs connected to said circuits, a switch arm movable to several positions in contact with said studs, and locking mechanism for locking said switch arm in any of said positions, said locking mechanism including a removable member which, upon being turned to the position in which it may be removed from the switch, locks said switch arm, and which, upon being turned to the position in which it is retained by the switch, unlocks 90 said switch arm. 95

10. In a switch for controlling a plurality of electric circuits, a plurality of switch studs connected to said circuits, a switch arm movable to several positions in contact 100 with said studs, and locking mechanism, including a removable member, for locking said switch arm in any of said positions, said locking mechanism being operated while the removable member is being turned 105 from the position in which it is retained by the switch to the position in which it may be removed therefrom.

In testimony whereof I affix my signature.
JAMES MYRVEN NAUL.
